J. J. RYAN.

SNOW REMOVING AND MELTING MACHINE.

APPLICATION FILED JUNE 21, 1919.

1,351,542.

Patented Aug. 31, 1920.

Fig. 3.

UNITED STATES PATENT OFFICE.

JOHN J. RYAN, OF BAYONNE, NEW JERSEY.

SNOW REMOVING AND MELTING MACHINE.

1,351,542.

Specification of Letters Patent. Patented Aug. 31, 1920.

Original application filed January 28, 1919, Serial No. 273,612. Divided and this application filed June 21, 1919. Serial No. 305,853.

To all whom it may concern:

Be it known that I, JOHN J. RYAN, a citizen of the United States, and a resident of Bayonne, county of Hudson, State of New Jersey, have invented new and useful Improvements in Snow Removing and Melting Machines, of which the following is a specification.

The main features of the snow melting device of this invention were shown and described in an application filed by me under Serial No. 273,612, January 28, 1919, and this is a divisional application thereof.

The snow melting receptacle of this invention is adapted to be carried on or in a vehicle provided with a snow elevator, arranged to raise the snow from the ground and deposit it in the snow melting receptacle as the vehicle is caused to travel over snow covered ground.

Suitable means for heating the snow receptacle are provided, preferably oil burners, the construction and arrangement of the snow receptacle being of such a character as to fully economically utilize the heat of combustion of the fuel.

The body of the vehicle is substantially rectangular in form with the snow elevator at one end thereof, preferably the rear end.

The sides of the snow melting receptacle are inclined, terminating at the lower central part in a valve controlled spout through which the melted snow may, as occasion requires, be discharged. The combustion chamber into which the oil burners extend is located in the lower part at one end of the body, and from which the products of combustion first pass around the lower parts of the inclined sides, and through flues in the lower part of the receptacle when such are provided, into a chamber at the other end of the body, thence through horizontal flues located in the receptacle into a chamber above the combustion chamber, from

which they may be allowed to escape to afford freedom of draft when the fire is started; but, to fully utilize the heat it is proposed to continue this chamber as a flue extending along the upper part of the receptacle with a final opening or chimney at the elevator end of the body.

As a further means for melting the snow it is proposed to arrange pipes along the fore and aft inclined sides of the receptacle, extending from the water space at the bot-

tom and terminating in nozzles directed into the upper part thereof; the nozzles at the elevator end being preferably arranged to direct steam generated in the pipes in substantially a horizontal direction against the snow, as it falls from the elevator into the receptacle, to disperse it over the horizontal flues; the nozzles at the other end may be pointed downwardly to direct the streams of steam into the snow as it accumulates in the receptacle.

To more fully describe these and other features of the invention reference will now be directed to the accompanying drawings, in which:

Figure 1, represents a longitudinal vertical embodiment of this invention.

Fig. 2, is a plan view partly in section, taken on the line 2, 2, Fig. 1, and:

Fig. 3, is a transverse vertical section on the line 3, 3, Fig. 1.

The machine is represented in the drawings as a trailer provided with rear supporting wheels 4, 4, and supported at its front end on wheels 5, which may be part of a motor truck.

The body is a substantially rectangular tank 6, lined with fire brick or other heat resisting non-conducting material 7, wherever its walls are exposed to the atmosphere. At the rear end is secured the snow elevator 8, which is suitably inclined and extends from near the ground to the top of the body. This elevator may be operated from the wheels 4, 4, by means of suitable sprockets and chains 9, 10.

The snow receiving and melting receptacle 11, located in the tank body 6, has its front and back walls and the lower parts of its side walls inclined, the apex of which is provided with a spout 12, having a valve 13, through which the melted snow &c. may be discharged. A detachable pipe may be attached to this spout when it is desired to discharge the water &c. away from the side of the machine, as for instance if the machine be used to remove snow from car tracks, to allow the water to flow into a gutter or into a culvert at the side of a street.

A suitable and preferred means for heating the snow in the receptacle is by the use of oil, burners 14, for this purpose being located at the front of the machine and arranged to direct the burning oil into a chamber 15, formed by the horizontal partition

16, extending from the receptacle to the front wall of the tank body.

Flues extend through the receptacle fore and aft thereof. The products of combustion of the oil issuing from the nozzles of the burners 14, pass from the chamber 15, around the lower part of the receptacle and through flues 17, if they be arranged in the lower part of the receptacle, and into the rear chamber 18, then through the horizontal flues 19, into the chamber 20, above the combustion chamber at the forward part of the machine. A passage or flue 21, extends from the chamber 20, over or through the upper part of the receptacle, from which the products of combustion may escape by the chimney 22, which may be provided with an ordinary damper device 23. The chamber 20, may also be provided with a damper or valve controlled outlet 24, which may, if desirable, be opened when the fire is started.

To add to the snow melting capacity of the machine pipes 25, are arranged adjacent the fore and aft walls of the receptacle in the heating spaces, their lower ends being connected to the lower part of the receptacle, containing water from the melted snow, their upper ends terminating in nozzles projecting in the receptacle above the flues 19, the nozzles 26, at the elevator end of the machine being arranged to direct the streams of water or steam issuing from them against the snow as it falls from the elevator and so scatter or disperse it through the receptacle. The nozzles 27, of the pipes at the fore part of the machine are preferably directed downwardly to direct the streams issuing from them on to the snow should it accumulate about the flues 19. Steam generated in the pipes 25, will as it issues from the nozzles 26 and 27, greatly assist in melting the snow.

An oil tank 28, and an air tank 29, are carried on the top of the body 6; said air tank supplied with air under suitable pressure by an air pump 30, whose motive power may be of any suitable character, as for instance it may be driven directly or indirectly by one of the supporting wheels of the machine. It is shown connected to the upper part of the elevator by a crank and rod 31. A pipe 32, supplies oil from the tank 28, to the burners 14, and compressed air is supplied to the burners from the tank 29, by the pipe 33. These devices may be of ordinary construction, provided with regulating valves &c. and need no further description here.

60 A door 34 at the side of the combustion chamber 15, provides entrance to said chamber for cleaning and repairing purposes and for lighting the oil. Other doors may be provided for access to the other chambers, 65 as indicated at 35.

It will be understood the invention may be advantageously used, applied to a stationary snow melting plant; the snow melting receptacle or apparatus being adequately housed or inclosed with suitable heating means, and with provisions for supplying snow to the receptacle substantially as before set-forth.

I claim:

1. A snow removing and melting machine, 75 comprising a tank vehicle, a snow receptacle located in the tank body and having its front and back walls and the lower parts of its sides inclined, a discharge spout at the apex of the inclined walls and sides, a combustion chamber at the lower part of the front of the tank body, burners in said chamber, a chamber at the rear of the tank body communicating with the combustion chamber around the lower part of the snow 85 receptacle, a chimney chamber above the combustion chamber, and flues arranged fore and aft through the snow receptacle for the products of combustion to pass from the rear chamber to the chimney chamber. 90

2. A snow removing and melting machine, comprising a tank vehicle, a snow receptacle located in the tank body and having its front and back walls and the lower parts of its sides inclined, a discharge spout at 85 the apex of the inclined walls and sides, a combustion chamber at the lower part of the front of the tank body, burners in said chamber, a chamber at the rear of the tank body communicating with the combustion chamber around the lower part of the snow 100 receptacle, a chimney chamber above the combustion chamber, a passage or flue extending from the chimney chamber rearwardly over the upper part of 105 the receptacle and having an outlet, and flues arranged fore and aft through the snow receptacle.

3. A snow removing and melting machine, 110 comprising a tank receptacle, a snow receptacle located in the tank body and having its front and back walls and the lower parts of its side walls inclined, a discharge spout at the apex of the inclined walls and sides, a combustion chamber at the lower part of 115 the front of the tank body, burners in said chamber, a chamber at the rear of the tank body communicating with the combustion chamber around the lower part of the snow 120 receptacle, a chimney chamber above the combustion chamber, flues arranged fore and aft through the snow receptacle, and pipes extending from the lower part of the receptacle upwardly adjacent the walls thereof and terminating in nozzles directed 125 into the upper part of said receptacle.

4. A snow melting machine, comprising a receptacle having its front and back walls and the lower parts of its sides inclined, a downwardly directed spout at the apex of 130

the inclined walls and sides, means for heating the receptacle including chambers at the front and back thereof and horizontal flues extending through the receptacle affording 5 communication between the chambers.

5. A snow melting machine, comprising a receptacle having its front and back walls and the lower parts of its sides inclined, a downwardly directed spout at the apex of 10 the inclined walls and sides, means for heating the receptacle including a combustion chamber at one end thereof, a chamber at the other end in communication therewith around the lower part of the receptacle, a 15 chamber above the combustion chamber, a passage or flue extending over the upper part of the receptacle from this chamber, and horizontal flues in the receptacle connecting this chamber and the chamber at 20 the other end of the receptacle.

6. A snow melting machine, comprising a receptacle having its front and back walls and the lower parts of its sides inclined, a spout at the apex of the inclined walls and 25 sides, means for heating the receptacle, horizontal flues extending through the receptacle, and pipes connected to the lower part of the receptacle extending upwardly adjacent the sides thereof and terminating in

nozzles directed into the upper part of the 30 receptacle.

7. A snow melting machine, comprising a receptacle having its front and back walls and the lower parts of its sides inclined, a downwardly directed spout at the apex of 35 the inclined walls and sides, means for heating the receptacle including a combustion chamber at one end thereof, a chamber at the other end in communication therewith around the lower part of the receptacle, a 40 chamber above the combustion chamber, a flue or passage from this chamber extending over the upper part of the receptacle and having an outlet to the air and flues passing through the receptacle connecting the chamber 45 above the combustion chamber with the chamber at the other end of the receptacle and pipes connected to the lower part of the receptacle extending upwardly adjacent the sides thereof and terminating in nozzles di- 50 rected into the upper part of the receptacle.

Signed at New York, county and State of New York, this 18 day of June, 1919.

JOHN J. RYAN.
